CLAIM

The ornamental design for a ridged foam dart with cap, as shown and described.

DESCRIPTION

FIG. 1 is a first perspective view of a ridged foam dart with cap showing our new design;

FIG. 2 is a front view thereof;

FIG. 3 is a back view thereof;

FIG. 4 is a left side view thereof;

FIG. 5 is a right side view thereof;

FIG. 6 is a top view thereof

FIG. 7 is a bottom view thereof; and,

FIG. 8 is a second perspective view thereof.

The portions of the design shown in broken lines are for the purpose of illustrating environment only and form no part of the claimed design.
